UNITED STATES PATENT OFFICE.

JOHN O. HEINZE, OF SPRINGFIELD, OHIO, ASSIGNOR TO THE JOHN O. HEINZE COMPANY,
OF SPRINGFIELD, OHIO, A CORPORATION OF OHIO.

CIRCUIT-CONTROLLING DEVICE.

1,208,961.

Specification of Letters Patent. Patented Dec. 19, 1916.

Application filed December 8, 1915. Serial No. 85,737.

To all whom it may concern:

Be it known that I, JOHN O. HEINZE, a citizen of the United States, residing at Springfield, in the county of Clark and State of Ohio, have invented certain new and useful Improvements in Circuit-Controlling Devices, of which the following is a specification.

This invention relates to improvements in controlling mechanism for electric circuits, the mechanism being more particularly adapted for controlling the lighting, ignition and starting circuits for motor vehicles employing internal combustion engines for the motive power.

An object of the invention is to provide a controlling mechanism which will be compact in form so as to bring the operating devices for the same at a common point in convenient reach of the operator.

A further object of the invention is to provide a mechanism of the character referred to in which but a single operating device is employed for establishing the different lighting and ignition circuits, having associated therewith and controlled thereby an operating device for the starting circuit.

A further object of the invention is to provide means whereby the starting operating device is locked against operation under certain conditions, such for instance as when the vehicle is at rest with the ignition off and with the lights either out entirely or dimmed.

A further object of the invention is to provide means whereby the operating devices for the lighting and ignition circuits may be locked against operation in certain positions of the same.

A further object of the invention is to simplify and cheapen the construction of mechanism of this character and also to make more effective the operation thereof.

In the accompanying drawings; Figure 1 is a front elevation of a mechanism embodying my improvements. Fig. 2 is a longitudinal section of the same on the line 2—2 of Fig. 1. Fig. 3 is a longitudinal section of the lock for the operating device for the lighting and ignition circuits, showing the parts in a different position from that shown in Fig. 2, that is, in unlocked position. Fig. 4 is a section on the line 4—4 of Fig. 2 showing the locking devices for the

starter operating device. Fig. 5 is a section showing the parts of Fig. 4 in a different position. Fig. 6 is a perspective view of one of the parts of the locking devices for the starter operating rod. Fig. 7 is a side elevation of the distributor, one of the insulated supports and some of the circuits. Fig. 8 is an end view of the distributor, the wipers for the same and the central insulated support. Fig. 9 is a side view of the distributor. Fig. 10 is a view of the opposite end of the distributor from that shown in Fig. 8. Fig. 11 is a perspective view of the distributor. Fig. 12 is a section on the line 12—12 of Fig. 10. Fig. 13 is a diagrammatic view of the periphery of the distributor. Fig. 14 is a diagrammatic view of the various circuits including the distributor and electrical sources. Fig. 15 is a rear elevation of the central partition showing the contacts for the generator switch. Fig. 16 is a front elevation of the rear wall of the casing showing the contacts for the starter switch.

The parts of the mechanism are inclosed by a cylindrical casing 1, having a circular front plate 2 and a rear wall composed of two disks 3 of insulating material and a metallic disk 4 inclosed between the disks 3 to lend strength thereto; the disk 4, however being of smaller diameter than the disks 3 so as to be out of contact with the casing 1. There is also provided a centrally arranged partition consisting of a series of disks 5 of insulating materials and an interposed metallic strengthening disk 6 of less diameter than the disks 5 so as to be out of contact with the casing 1. Rods 1^a and spacing sleeves 1^b serve to connect the parts and hold the same in spaced relation. The casing is preferably inserted through an opening in the dash 7 of the vehicle with the plate 2 on and secured to the driver's side thereof. The plate 2 is provided with a central aperture and secured to the plate about this aperture is a disk 8 upon which are placed characters to indicate the different positions in which the main operating device may be placed.

The main operating device is in the nature of a crank arm 9 secured to a sleeve 10 which extends through a bushing 11 inserted in the central aperture in the plate 2 and secured thereto. The rear end of the sleeve has secured thereto a distributor, the main

body of which is formed of a disk 12 of insulating material in which is a contact member consisting of a circular ring 13 extending about the rear end of the disk 12, a portion 14 which extends substantially, in the present case, three-fifths of the way about the rear portion of the periphery of the disk 12, and an extension 15 on the portion 14 which projects to the forward end of the disk 12; the contact parts being all preferably constructed integrally.

Arranged about the distributor with their free ends in contact therewith is a series of spring wipers 16, 17, 18 and 19 four of which are employed in the present case. These wipers are connected to and supported by blocks 20 which project forwardly from the central partition of the casing so as to bring the free ends of the wipers in the plane of the distributor; the wiper 16, however, lying in a different plane from the other wipers; the wiper 16 being in the same plane as the contact portion 14 of the distributor while the wipers 17, 18 and 19 are in the same plane as the contact extension 15 of the distributor. A U-shaped wiper or conductor 21 (Figs. 7 and 8), supported from the central partition, is constantly in contact with the ring 13 of the distributor and is connected by wires 22, 23 and 24 to a storage battery 25 and generator 26, respectively, so as to furnish current to the distributor. (See Fig. 14.)

The wiper 16 is for the ignition, a wire 27 connecting the wiper with the ignition devices. The wipers 17, 18 and 19 are for furnishing current to the lights, represented by 28. The wiper 17 is connected to the lights by wire 29, resistance 30, wire 31 and wire 32. The wiper 18 is connected to the lights by wire 32. Wiper 19 is connected to the lights by wire 33, wire 29, resistance 30, wire 31 and wire 32. The other side of the lights are connected to ground by the wire 34.

In the "Off" position of the main operating lever 9, all of the wipers rest upon the disk 12. Assuming now that the lever is moved to the right, to the position corresponding to "Lights off, Ign. on," the wiper 16 will ride into the recess 14^a formed in the end of the contact portion 14 and establish a circuit to the ignition devices. Recesses 12^a are also preferably formed in the insulated part of the distributor within which the other wipers 17, 18 and 19 drop for the purpose of yieldably holding the distributor in the different operative positions; that being the primary purpose of all of the recesses.

If the main operating lever is now moved to the next position, corresponding to "Ign. on, Lights dim," the wiper 17 will drop into the recess 15^a in the contact extension 15 and establish a circuit to the lights through

the resistance 30, at the same time the wiper 16 will have kept its contact with the contact portion 14 so as to maintain the circuit to the ignition devices, this wiper now resting in the recess 14^b. If the operating handle 9 is now moved to the next position corresponding to "Ign. on, Lights bright," the wiper 18 will next drop into the recess 15^a of the contact portion 15 and establish a circuit to the lights through the wire 32 as before explained, and as before the wiper 16 will ride about the contact portion 14 to still maintain the circuit with the ignition dropping into the recess 14^c. Assuming now that the main operating lever is thrown to the next position, which corresponds to "Lights dim, Ign. off," the wiper 19 will drop into the recess 15^a of the contact portion 15 and establish the circuit before described through the resistance 30 to the lights for the purpose of dimming the lights, but the wiper 16 will now have ridden off the contact portion 14 onto the disk 12 and destroyed the circuit to the ignition devices. If the main operating lever is now thrown to the "Off" position which corresponds to the position of the lever shown in Figs. 1 and 2, all of the wipers will be resting on the disk 12 and all circuits thus broken.

Slidably mounted in the sleeve 10 is a rod 35 which constitutes the starter operating device, the rod being provided with a head 35^a to provide a convenient means for grasping it. The rod extends through an aperture 36 in the central partition and on the rear side of the partition is provided with a switch consisting of two contact members 37 and 38 (Fig. 2) which are mounted upon a sleeve 39 of insulating material and clamped between a flange on said sleeve and a nut 40 threaded on the said rod 35; washers 41 being preferably inserted between the nut and the member 37 and also between the sleeve 39 and a shoulder on the rod so as to firmly clamp the parts in position; the washer adjacent the switch member 37 being of insulating material to insulate the switch members from the rod 35. Each of the contact members 37 and 38 is of a cup-shape, with the walls of the cup slotted so as to form in effect a series of contact points. The member 38 is normally held in contact with two conductor plates 42 and 43 on the rear side of the central partition (Fig. 15) which are in electrical connection by conductors 44 with binding posts 45 (one of each of which is shown in Fig. 2) on the rear side of the end wall of the casing. A wire 45' connects one of the contact plates 42 with the generator and a wire 46 connects the other plate 43 with the battery so that a circuit is normally established with the generator and battery for charging purposes; a spring 47 interposed between the 130

nut 40 and the rear end of a housing 48 secured in an aperture in the rear wall of the main casing, serving to normally hold the switch member 38 in contact with the plates 42 and 43.

For starting purposes there is provided on the forward side of the rear wall two conductor plates 49 and 50 (Fig. 16) with which the switch member 37 makes contact when the rod 35 is pushed in against the tension of the spring 47. These contact plates are in electrical communication with binding posts on the rear wall of the main casing, one of which 49' is shown in Fig. 2. One of the contact plates 50 is connected by wire 51 and wire 46 with the battery, and the other conductor plate 49 is connected by wire 52 with the motor 53, the motor being connected to the battery by the wire 54. It will be noted that the first movement of the push rod breaks the contact between the switch member 38 and the contact plates 42 and 43 so as to break the circuit between the generator and the battery; this circuit being immediately automatically re-established so soon as pressure is removed from the push rod.

Means are provided for automatically locking the starter push rod when the operating lever 9 is in either the "Off" position or "Lights dim, Ign. off" position and for automatically unlocking the same when the lever 9 is thrown to any of the "Ign. on" positions. Referring to Fig. 2 it will be seen that the rod 35 is provided with a recessed portion 55 which extends about the entire periphery of the same. In line with this recessed portion is a pocket 56 in the sleeve 10 in which is located a ball 57, the ball being of a diameter substantially equal to the combined depth of the pocket and recess. Referring to Figs. 4, 5 and 6 it will be seen that the bushing 11 has a series of recesses 58, three in number, in the present case, so disposed that whenever the operating lever is turned to any one of the "Ign. on" positions, the pocket 56 will be brought in registry with one of these recesses 58 so that if the starter push rod is forced inwardly the ball 57 will be allowed to move out of the path of the forward wall of the recess 55 and thus unlock the rod. Whenever, however, the operating lever is in any of the other positions, the solid wall of the bushing will be presented to the ball and thus lock the rod. Means are also provided for locking the main operating lever 9 in either the "Off" position or the "Lights dim, Ign. off" position. Referring to Figs. 2 and 3, the rear side of the lever 9 is provided with a recess or chamber 59. Secured to the lever 9 and projecting upwardly into this chamber is a spring arm 60 having its free upper end provided with a button 61 which will normally spring into a

recess 62 in the plate 2, one of these recesses being located at each of the "Off" and "Lights dim, Ign. off" position. A revoluble thimble 63 in the lever 9 receives a key 64 the inner end of which extends through a bifurcated portion of the spring arm 60 and has a beveled projection 65, which when the key is turned engages one of the sides of the bifurcated portion of the spring arm, which is bent or inclined rearwardly as indicated at 66, so that the spring arm will be cammed forwardly to the position shown in Fig. 3 and thus unlock the lever 9. When the key is again turned to the position shown in Fig. 1 or removed entirely the spring arm 60 will automatically throw the button 61 into one of the recesses 62 when brought in registry therewith to lock the lever 9 in that position.

Having thus described my invention, I claim:

1. In an electric controlling mechanism, a plurality of electrical circuits, a main operating device arranged to be set at different positions to control said circuits, a second series of circuits, a second operating device associated with said main operating device for controlling said second series of circuits, means for locking said main operating device in certain positions of the same, and means controlled by said main operating device for locking said second operating device in certain operative positions of said main operating device and for unlocking said second operating device in certain other operative positions of said main operating device.

2. In an electric controlling mechanism, for motor vehicles, a plurality of electrical circuits, a main operating device for controlling the lighting and ignition circuits, and a second operating device for controlling the starter motor circuit, means for locking said main operating device in certain of its positions, and means controlled by said main operating device for locking said starter operating device in certain operative positions of said main device and for unlocking said starter operating device in certain other operative positions of said main operating device.

3. In a mechanism for controlling the electric circuits of motor vehicles, a plurality of electrical circuits, a main operating lever for controlling the lighting and ignition circuits, a push rod for controlling the starter motor circuit, means for locking said lever in certain positions thereof, and means controlled by the movement of said lever for locking said rod in certain operative positions of said lever and for unlocking said rod in certain other operative positions of said lever.

4. In a controlling mechanism for electric circuits for motor vehicles, a plurality of

electrical circuits, a main operating device for controlling the lighting and ignition circuits arranged to be set to certain positions, in some of which the ignition circuit 5 is closed and in some open, a starter operating device for closing the circuit for the starting motor, and means controlled by said main operating device for locking said starter operating device when the ignition 10 circuit is open.

5. In a controlling mechanism for electric circuits for motor vehicles, a plurality of electrical circuits, a main operating device for controlling the lighting and ignition circuits, 15 a revolute operating device arranged to be set to different positions to control the lighting and ignition circuits, in some of which positions the ignition circuit is open and in some closed, a push rod for controlling the starting circuit associated with said revolute device, and means controlled by said revolute device for locking said push rod when the ignition circuit is open and for unlocking said push rod when the ignition 25 circuit is closed.

6. In a controlling mechanism for electric circuits, a plurality of electrical circuits, a dial having characters indicating said circuits, a revolute member movable about said 30 dial for controlling the circuits indicated on said dial, a starter motor for the circuits, a spring-pressed slideable member associated with said revolute member for controlling said starter motor circuit, and means operated by said revolute member for controlling the movement of said slideable member.

7. In a mechanism for controlling electric circuits for motor vehicles, a plurality of electrical circuits, a dial having characters 40 indicating said circuits, a revolute member movable about said dial for controlling the circuit indicated thereon, a starter motor circuit, a starter operating device for controlling said starter circuit, and means operated by said revolute member for controlling said starter operating device.

8. In a mechanism for controlling electric circuits for motor vehicles, a plurality of electrical circuits, a dial having characters 50 thereon indicating said circuits, a revolute member movable about said dial for controlling the circuits indicated thereon, a starter motor circuit, a starter push rod slidably mounted in the axis of said revolute member for controlling said starter motor circuit, and means controlled by said revolute member for locking and unlocking said push rod according to the position of said revolute member about said dial.

60 9. In a mechanism for controlling electric circuits, a plurality of electrical circuits, a main operating device for controlling the lighting and ignition circuits, a second operating device associated with said main operating device for controlling the starting gen-

erator and battery circuits, and means operated by said main operating device for controlling said second operating device.

10. In a mechanism for controlling electric circuits for motor vehicles, a plurality of 70 electrical circuits, a main operating device for controlling the lighting and ignition circuits, a second operating device for controlling the starter, generator and battery circuits, and means controlled by said main operating device for locking said second operating device when the ignition circuit is open and for unlocking the same when said ignition circuit is closed.

11. In a controlling mechanism for electric 80 circuits for motor vehicles, a plurality of electrical circuits, a dial plate, a crank arm having a sleeve or hub journaled in said plate, a distributor connected with said sleeve to control certain of said circuits determined by the position of said crank arm, an operating rod journaled in said sleeve, and an electric switch connected with said rod independent of said distributor.

12. In a mechanism for controlling electric 90 circuits for motor vehicles, a plurality of electrical circuits, a dial plate, a crank arm having a hub journaled in said plate, a distributor connected to said hub for controlling the light and ignition circuits, a starter operating rod slidably mounted in said hub, and a switch for the starter motor connected with said rod.

13. In a mechanism for controlling electric 100 circuits for motor vehicles, a plurality of electrical circuits, a dial plate, a crank arm having a hub journaled in said plate, a distributor connected with said hub for controlling the light and ignition circuits, a spring-pressed rod slidably mounted in said hub, and switches connected with said rod independent of said distributor for controlling the battery and generator circuits.

14. In a mechanism for controlling electric 110 circuits for motor vehicles, a plurality of electrical circuits, a dial plate, a crank arm having a hub journaled in said plate, a distributor connected with said hub for furnishing current to lighting and ignition circuits, an operating rod slidably mounted in said hub, switches connected with said rod for controlling the motor battery and generator circuits, means controlled by said crank arm for locking and unlocking said operating rod, and means for locking said 115 crank arm in certain of its positions.

15. In a mechanism for controlling electric 125 circuits for motor vehicles, a plurality of electrical circuits, a dial plate, a crank arm having a hub journaled in said plate, a distributor connected with said hub, a spring pressed operating rod journaled in said hub, said hub having a pocket and said rod having a peripheral recess in line with said pocket and a ball in said pocket and recess,

- said plate being provided with a series of recesses with which said pocket is adapted to be brought in registry in certain positions of said crank arm.
- 5 16. In a mechanism for controlling electric circuits for motor vehicles, a plurality of electrical circuits, a dial plate having a centrally arranged opening, a bushing in said opening connected with said plate, a crank 10 arm having a sleeve or hub, and a spring pressed circuit controlling rod slidably mounted in said sleeve or hub, said sleeve or hub having a pocket and said rod a peripheral groove coinciding with said pocket 5 and a ball in said pocket and groove, said bushing having a series of recesses with which said pocket and ball coincide in certain positions of said crank arm.
17. In a mechanism for controlling electric 20 circuits for motor vehicles, a plurality of electrical circuits, a revoluble operating device slidably mounted in the hub portion of said revoluble device, two switch members on said slideable operating device, a spring for normally holding one of said members in position to 25 close the circuit between the generator and the battery, contacts for the other switch member for closing the circuit between the battery and motor when said slideable device is moved against the tension of the spring, and means whereby the operation of said slideable device is controlled by said revoluble device.
18. In a mechanism for controlling electric 30 circuits for motor vehicles, a plurality of electrical circuits, a revoluble operating device for controlling the lighting and ignition 35 circuits, a second operating device slideably mounted in the hub portion of said revoluble device, two switch members on said slideable operating device, a spring for normally holding one of said members in position to 40 close the circuit between the generator and the battery, contacts for the other switch member for closing the circuit between the battery and motor when said slideable device is moved against the tension of the spring, and means whereby the operation of said 45 slideable device is controlled by said revoluble device.

In testimony whereof, I have hereunto set my hand this 4th day of December, 1915.

JOHN O. HEINZE.
